GARMENT HANGER

William P. Crockett, Jr., Chicago, Ill., assignor to
Mackie-Lovejoy Manufacturing Co., Chicago,
Ill., a corporation of Illinois

Application January 28, 1949, Serial No. 73,338

6 Claims. (Cl. 223—96)

1

This invention relates to an improved garment hanger of the clamping type.

In a device of this type jaws are provided to engage the garment to be supported and the jaws in turn are supported by arms or other means which are hingedly connected to each other. Means are provided for urging the jaws into clamping engagement with each other, and separate spring means have generally been provided to urge the jaws apart when the clamping means is released. Thus, the insertion of a garment between the jaws is facilitated.

An object of this invention is to provide a garment hanger in which the parts are so shaped and arranged to avoid the use of a separate spring for urging the jaws apart.

Another object of this invention is to provide a garment hanger of the type referred to in which the jaws can be opened to practically any angular position without impairing the action of the means which urge the jaws apart. When a separate spring is used to urge the jaws apart, not only does the spring limit the extent to which the jaws may be opened, but if the jaws are inadvertently opened to a position which approaches the limiting position, the spring is likely to be deformed in such a manner that it will thereafter impair the smooth operation of the garment hanger.

Another object is to provide an improved garment hanger in which the resilience of the wire stock from which the arm and crank elements are made serves to hold the jaws in gripping engagement with each other when the clamping lever is operated, and which also serves to urge the jaws away from each other when the clamping lever is in its unoperated position.

I have found that the foregoing objects may be attained by so shaping the two jaw supporting means that as the jaws are brought into garment clamping position, the jaw supporting means will be stressed in such a manner that they will tend to spring apart. In particular, portions of the jaw supporting means are disposed in crossed relationship with respect to each other, and one of said portions acts as a cam so that the jaw supporting means can be stressed.

In describing my invention, I have shown it as applied to a garment hanger of the type shown in Deknatel Patent No. 1,955,792, in which the hingedly connected arms are provided with crank portions. A clamping lever is pivotally mounted on one crank portion and engages the crank portion of the other arm to actuate the jaws. However, my invention is equally applicable to gar-

2

ment hangers employing other types of clamping means for urging the jaws into clamping engagement with each other and other types of hinged connection between the jaws.

With reference now to the drawings in which like reference numerals designate like parts:

Fig. 1 is a perspective view of a preferred embodiment of my invention, showing the jaws in an open position;

10 Fig. 2 is an inverted rear view of the device shown in Fig. 1;

Fig. 3 is a fragmentary plan view of the device shown in Figs. 1 and 2, showing the relationship of certain of the parts when the jaws are in open position;

Fig. 4 is a front elevation of the device shown in the preceding figures, but with jaws in closed position;

Fig. 5 is an enlarged detailed view taken along line 5—5 of Fig. 4;

Fig. 6 is a view similar to Fig. 4 but showing the parts in open position, and

Fig. 7 is a detailed sectional view taken along line 7—7 of Fig. 6.

25 The garment hanger comprises a pair of jaws 10 and 11 which are preferably made from wood and may be provided with felt pads on their clamping surfaces. The jaws are supported by separate rods or wires, the ends of which are suitably secured to the jaws. The rod supporting jaw 10 is provided with jaw arm portions 13 at either end which are separated by an intermediate portion which includes a crank 14. The rod supporting jaw 11 includes jaw arm portions 16 which are separated by an intermediate portion comprising a crank 17 and cam portions 30.

30 The two portions between the cam portions 30 and the jaw arms 16 are formed into helices 19 which embrace correspondingly disposed pintle portions 24 on the opposite rod. Thus, the jaws 10 and 11 are hinged mounted with respect to each other.

35 The jaws 10 and 11 are brought into clamping engagement with each other by means of a clamping lever 20 which is pivotally mounted on crank 17. The clamping lever is provided with a camming portion 22 which is adapted to engage and ride over the crank 14 in order to bring the jaws into closed or clamping position, as

40 shown in Fig. 5.

45 If desired, the crank 14 may be provided with a roller bearing as shown in the aforementioned patent in order to reduce friction and wear.

50 The crank 14 is separated from the pintle portions 24 by means of bends 31. The rod support-

ing jaw 11 is so shaped that the cam portions 30 thereof engage the other rod at the inner surfaces of the bends 31 when the jaws are brought into closed position. The relationship of the parts in open position is best shown in Figs. 3 and 7. When the parts are brought into closed position, as shown in Figs. 4 and 5, the cam portions 30 tend to squeeze the opposite legs of the crank 14 towards each other, which introduces the stress which tends to cause the jaws to spring apart. The pintle portions 24 are somewhat longer than the length of the helices 19 so as to permit the longitudinal movement of the pintle portions which results when the parts are stressed.

One advantage of the present arrangement is that the parts may be so designed that the cam portions 30 do not engage the bends 31 until the jaws are fairly close to each other, such as 30° apart. When the jaws are opened beyond this 30° position there is no binding action which serves to limit the degree of opening, since the helices and pintle portions are aligned with each other, and since the crank 14 is entirely out of engagement with the cam portions 30 in such open positions.

The operation of the device has been described in connection with the description of the various parts. To summarize, the jaws of the garment hanger are normally biased into about the open position shown in Fig. 1. This permits the garment to be placed between the jaws 10 and 11. Then the clamping lever 20 is swung upwardly so that the camming portion 22 engages the crank 14 and causes the jaws to close. At the same time, the cam portions 30 of one rod engage the other rod and stress the latter so that when the clamping lever is subsequently released, the jaws will spring apart.

As shown in Fig. 1, the outer end of the clamping lever 20 may be formed into a hook so that the garment hanger may be conveniently supported from a clothes rod. However, other supporting means may be provided, and the clamping lever may be utilized solely for clamping purposes, if so desired.

The general U-shape of the crank 14 and of the cam portions 30 and crank 17 permit each to be deformed in a direction parallel to the axis of the hinge. When the clamping lever 20 is brought into clamping engagement with the crank 14 the rods are deformed in a peripheral direction, which is perpendicular to the hinge axis. Due to this arrangement the rods may be simultaneously subjected to different stresses which do not tend to neutralize each other because the deforming forces are applied in directions perpendicular to each other. Thus the jaws will always tend to spring apart, even though they are securely held in clamped position by means of the clamping lever.

The deformation due to the action of the cam portions 30 may be either a deformation of the crank 14, which tends to squeeze the legs together, or it may be a deformation of the crank 17 and the cam portions 30, which tend to spread the legs of the crank and cam portions apart, or it may be a combination of both. In either event, the helices 19 are urged outwardly with respect to the pintle portions 24 when the jaws are brought into closed position.

The two rods which support the jaws 10 and 11 may be formed from any suitable wire stock which has a certain amount of resilience.

The principles of my invention may also be

applied to other types of garment hangers other than the particular type shown. For instance, the rod members may be caused to engage each other at some point along the jaw arm portions 13 and 16, and clamping means other than that shown herein may be provided.

Although only a preferred embodiment of my invention has been described and shown herein, it will be obvious that various modifications and changes may be made in the construction shown without departing from the spirit of my invention as shown in the appended claims.

I claim:

1. In a garment hanger having two garment clamping jaws, separate means for supporting each of said jaws, said supporting means being hingedly connected to each other to provide a hinged connection for said jaws, one of said supporting means being provided with a substantially radially disposed portion adapted to be deformed in a direction substantially parallel to the axis of said hinged connection, and the other one of said supporting means being provided with a cam portion adapted to engage said radially disposed portion as said jaws are brought into closed position whereby one of said supporting means is stressed in such a manner that said jaws will tend to spring apart, and clamping means acting on said supporting means in a peripheral direction to urge said jaws into closed position, at least one of said supporting means being formed of resilient material.

2. A supporting device comprising two clamping jaws, means for supporting each of said jaws for relative movement about an axis, a resilient U-shaped crank portion on one of said supporting means disposed in a plane substantially parallel to a plane passing through said axis so that the legs thereof may be deformed in an axial direction, said supporting means having portions adapted to engage each other as said jaws are brought into closed position in such a manner that said legs will be deformed in an axial direction whereby said jaws will tend to spring apart.

3. A supporting device comprising two clamping jaws, means for supporting each of said jaws for relative movement about an axis, a hinged connection for said supporting means, a resilient U-shaped crank portion on one of said supporting means disposed in a plane substantially parallel to a plane passing through said axis so that the legs thereof may be deformed in an axial direction, said supporting means having portions adapted to engage each other as said jaws are brought into closed position in such a manner that said legs will be deformed in an axial direction whereby said jaws will tend to spring apart and clamping means acting on said supporting means in a peripheral direction to urge said jaws into closed position.

4. A garment hanger comprising two jaws, a rod for supporting each of said jaws for pivoted movement with respect to each other, at least one of said rods being formed of resilient material, each of said rods comprising two end portions bent to form jaw arms and an intermediate portion including a crank, the crank for one of said rods having substantially radially disposed legs, and the intermediate portion of the other of said rods being provided with cam surfaces disposed in crossed relationship with each of said crank legs when said jaws are in closed position, the relationship between said crank arms and said cam surfaces being such

that as said jaws are being brought into said closed position, said cam portions and said radially disposed crank arms will engage each other so as to stress at least one of said rods, the reaction between said rods at the points of engagement serving to cause the jaws to spring apart from closed position.

5. A garment hanger comprising two jaws, a rod to support each of said jaws for pivoted movement with respect to each other, each of said rods comprising two end portions bent to form jaw arms and an intermediate portion including a U-shaped resilient crank, one of said rods having axially aligned helical portions at points between said crank and said jaw arms and the other of said rods having axially aligned pintle portions at points between said crank and said jaw arms, said helical portions surrounding said pintle portions to provide a hinged connection between said rods, a clamping lever pivotally mounted on one of said cranks and adapted to engage the other of said cranks to bring said jaws into clamping engagement with each other, one of said rods having cam portions engaging the legs of the crank of the other of said rods when said jaws are in closed position whereby the legs of said crank will be stressed and serve to urge the jaws apart from closed position.

6. A supporting device comprising two clamping jaws, means for supporting each of said jaws for relative movement about an axis, each

of said supporting means comprising two end portions bent to form jaw arms and an intermediate portion including a pair of spaced hinge elements, the hinge elements of one of said means cooperating with the hinge elements of the other to provide a hinged connection, the intermediate portion of one of said supporting means including a resilient member connecting said spaced hinge elements to permit relative movement of said pairs of said hinge elements with respect to each other in an axial direction, said supporting means having portions adapted to engage each other as said jaws are brought into closed position in such a manner that said resilient member will be deformed in an axial direction whereby said jaws will tend to spring apart.
